UNITED STATES PATENT OFFICE

RALPH J. WELLS, OF DAYTON, OHIO

ADJUSTABLE RAIL CLAMP

Application filed May 24, 1929. Serial No. 365,752.

My invention relates to railway track construction and more particularly to an adjustable rail clamp for securing the track rail to a tie or sleeper.

- 5 In the installation and especially in the repair of railway trackage, it is desirable that the track rail and fastening means may be relatively adjustable through a limited range to compensate for wear, inaccuracies of installation and to insure proper gauge. The use of rail clamps engaging the base flange of the rail has been more or less common. Such rail clamps ordinarily do not provide for adjustment toward and from the rail, or where 10 such adjustment has been attempted the fastening devices are not secure and are likely to become loosened by the vibration and strains incident to passing traffic.

The present invention pertains to a clamp 20 plate having locking means for securing it in different positions of relative adjustment including an eccentric collar revolvably mounted upon a clamp bolt and engagable with the clamp plate in various positions of revoluble 25 adjustment, the clamp plate being laterally shiftable to various positions in accordance with the revoluble adjustment of the eccentric locking member.

The object of the invention is to simplify 30 the structure as well as the means and mode of operation of adjustable clamp means whereby such clamp means will not only be cheapened in construction, but will be more efficient in use, positive in operation, capable of being easily and quickly adjusted to different relative positions and unlikely to get out of repair.

A further and important object of the invention is to provide locking means for positively holding the clamp plate in any one of several positions.

A further object of the invention is to provide a locking means which, while capable of being easily and quickly relieved when the occasion requires, will not be subject to accidental release.

A further and important object of the invention is to provide such a construction having few parts which may be cheaply produced by casting or by forging, requiring minimum

machining operation, the parts of which are interchangeable.

With the above primary and other incidental objects in view, as will more fully appear in the specification, the invention consists of the features of construction, the parts and combinations thereof and the mode of operation or their equivalents as hereinafter described and set forth in the claims.

Referring to the accompanying drawings 60 wherein is shown the preferred, but obviously not necessarily the only form of embodiment of the invention, Fig. 1 is a perspective view of a short portion of a railway rail to which the present adjustable clamp device has been applied.

Fig. 2 is a detail transverse sectional view through the railway rail and adjustable clamp members applied to the base flanges on opposite sides of the rail.

Fig. 3 is a top plan view somewhat diagrammatic illustrating the range of adjustment of the clamp plate and locking collar.

Figs. 4 and 5 are a top plan and sectional view respectively illustrating a modification.

Fig. 6 is a top plan view of the clamp plate with the locking collar removed.

Like parts are indicated by similar characters of reference throughout the several views.

Referring to the drawings, 1 indicates the rail and 2 the sleeper or tie upon which the rail 1 rests. The base flange of the rail is engaged by an overlapping clamp plate 3. This clamp plate 3 is preferably, though not necessarily, provided with a fulcrum bead or rib 4 on its under face adjacent to the outer margin upon which the plate is supported in slightly elevated relation for limited tilting movement into firm clamping engagement with the rail flange. The clamp plate 3 is provided with an enlarged countersunk opening 5 through which extends a clamp bolt 6 or a lag screw 7 or other clamping stud having engagement with the tie or sleeper 2. The counterbore or flare of the opening 5 forms a socket or seat for a revoluble collar 8 having therein an eccentric opening through which the bolt 6 or lag screw 7 or other clamp stud extends. The collar 8 is thus revolvably

but eccentrically mounted upon such bolt or stud. This locking collar 8 is preferably, though not necessarily, of polygonal shape with which contour the socket or recess in the clamp plate 3 agrees. The locking collar 8 is engageable in such socket or seat within the clamp plate in different positions of revolute adjustment. The seat within the socket or recess and the under face of the locking collar 8 are preferably, though not necessarily, inclined or of substantially pyramidal form to insure a wedging or tight seating engagement.

By turning the locking collar 8 throughout varying degrees of partial rotation about the stud or bolt and correspondingly shifting the clamp plate 3 to bring its socket or recess into registry with the adjusted locking collar, such clamp plates may be secured in different positions of relative adjustment, a few of which have been illustrated in Fig. 3. When the collar 8 is interengaged with the clamp plate 3 in any one of these various positions and so held by the clamping adjustment of the bolt 6 or screw 7, the clamp plate 3 is positively held against relative shifting motion.

In Figs. 4 and 5, there is shown a modification wherein a circular locking collar 9 is seated in a corresponding circular recess or socket in the clamp plate and interlocked therewith by the engagement of a lug or projection 10 upon the clamp plate within one or another of a series of peripheral notches 11 in the locking collar. While the polygonal form of locking device, illustrated in Figs. 1 to 3, is to be preferred, it is obvious, however, that other forms of device may be utilized. In order to afford a larger number of different effective positions of relative adjustment of the clamp plate and bolt and to effect such adjustment in comparatively small steps, the center of the eccentric hole for the bolt 6 is not located on either a diameter bisecting opposite flat faces of the polygonal locking collar 8 nor on a diameter bisecting opposite angles thereof, but in a position intermediate such diametrically lines as shown in Fig. 3. This enables variation of adjustment to six different degrees.

To prevent the accidental loosening of the nut upon the bolt 6 by the vibration incident to passing traffic, the contact faces of the nut and the lock collar 8 are preferably though not necessarily radially toothed as indicated at 12. The teeth are of angular formation having a rather extended inclined face in the direction of rotation of the nut, enabling the teeth to ride rather easily over one another as the nut is tightened. Inasmuch as the teeth are rather shallow, the bolt will yield sufficiently against the resiliency of the tie to permit such teeth to pass. The opposite faces of the teeth are inclined more abruptly, being disposed at an approximately forty-five degree angle. This will normally resist re-

turn movement of the nut under influence of vibration. However, by application of power through a long-handled wrench affording the necessary leverage, the nut can be backed off. In such reverse movement the more abruptly inclined faces of the teeth will ride one over the other.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect and the invention is, therefore, claimed in any of its forms or modifications within the legitimate and valid scope of the appended claims.

Having thus described my invention, I claim:

1. An adjustable rail clamp including a clamp plate having a polygonal socket therein and an enlarged opening within the socket, a clamp bolt extending through such opening in relation with which the clamp plate is capable of lateral shifting movement in various directions relative to the bolt, a polygonal collar adapted to fit within said socket in various positions of revolute adjustment, said collar being eccentrically mounted upon said clamp bolt for revolute adjustment thereabout, the engagement of said polygonal collar in said polygonal socket in different positions of revolute adjustment about the bolt serving to lock said clamp plate in its different positions of adjustment against the lateral shifting motion.

2. An adjustable rail clamp comprising a clamp member, a clamp bolt in relation with which the clamp member is capable of relative shifting movement, said clamp member having a seat in the top face thereof and a lock collar eccentrically mounted relative to the clamp bolt for revolute movement thereabout, said collar having locking engagement within the seat in the top face of the clamp member in different positions of its revolute adjustment to hold the clamp member against shifting movement and a clamp nut on said bolt bearing upon said lock collar.

3. In a device of the character described, a clamp bolt, a pyramidal collar having an eccentrically positioned hole through which the bolt extends, and an adjustable member having therein an enlarged opening for the bolt,

and a seat shaped to receive the collar with which the collar is engageable in various positions of revoluble adjustment.

4. In an adjustable rail clamp, a clamp plate having an enlarged opening therein for a clamp stud, a washer having seated engagement with the top face of the clamp plate in various positions of revoluble adjustment, said washer having therein an eccentrically positioned hole through which the clamp stud extends and a clamp nut on said stud bearing upon said washer.

5. In an adjustable rail clamp, a clamp plate having therein a polygonal socket, a polygonal washer engageable in said socket in various positons of revoluble adjustment, said washer having therein an eccentrically positioned hole for a stud, and a clamp stud ex-
tending through the clamp plate and through
the eccentrically located hole in the washer.

6. In an adjustable rail clamp, a clamp plate having therein a pyramidal socket, a correspondingly shaped insert for engage-
ment in the socket in various positions of
revoluble adjustment, said insert having
therein a hole located in eccentric position,
and a clamp stud extendible through said
hole, the clamp plate being secured in various
positions of lateral adjustment by the en-
gagement of the insert in said socket in differ-
ent positions of revoluble adjustment about
the axis of the clamp stud.

7. In an adjustable rail clamp, a clamp plate, a locking collar engageable with the plate in different positions of revoluble ad-
justment, said collar having an eccentrically positioned hole therein, a clamp bolt extend-
ing through said hole and a clamp nut carried
thereby, and interlocking inclined teeth upon
the contact faces of the clamp nut and the
locking collar.

8. In an adjustable rail clamp, a clamp plate, a locking collar engageable with the plate in different positions of revoluble ad-
justment, said collar having an eccentrically positioned hole therein, a clamp bolt extend-
ing through said hole and a clamp nut carried
thereby, interlocking teeth upon the contact
faces of the clamp nut and the locking collar,
the lateral faces of the teeth being in-
clined to different degree with the faces suc-
cessively engaged during tightening ad-
justment of the nut inclined at a lesser degree
than those faces successively engaging upon
reverse adjustment of the nut.

9. In an adjustable rail clamp, a clamp plate, a locking collar engageable with the plate in different positions of revoluble ad-
justment, said collar having an eccentrically positioned hole therein, a clamp bolt extend-
ing through said hole and a clamp nut car-
ried thereby, and interlocking angular teeth

upon the contact faces of the nut and locking
collar.

In testimony whereof, I have hereunto set
my hand this 18th day of May, A. D. 1929.

RALPH J. WELLS.
